UNITED STATES PATENT OFFICE.

REUBEN B. THOMPSON, OF COHOES, NEW YORK, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,273,108.

Specification of Letters Patent. Patented July 16, 1918.

Application filed July 20, 1915. Serial No. 40,884.

To all whom it may concern:

Be it known that I, REUBEN B. THOMPSON, a citizen of the United States, residing at Cohoes, in the county of Albany, State of New York, have invented certain new and useful Improvements in Presser-Foots for Sewing-Machines, of which the following is a description, reference being had to the accompanying drawing, and to the figures of reference marked thereon.

The invention relates to new and useful improvements in a presser foot for sewing machines and more particularly to a presser foot which is adapted to guide upturned edges of fabric sections to horizontally disposed trimming members.

An object of the invention is to provide a presser foot of the above character which is formed with a guiding slot extending rearwardly from the front end thereof to a point in advance of the needle opening, wherein the said presser foot is divided longitudinally to form independent foot sections extending on opposite sides of said slot and wherein said sections are supported so that one section may vertically yield independent of the other.

A further object of the invention is to provide a presser foot of the above character wherein the stationary trimming blade is mounted on the main section of the presser foot and disposed so that the trimming blades operate at the inner end of the guiding slot to sever the upturned edges of fabric sections passing along the slot.

A still further object of the invention is to provide a presser foot and trimming mechanism of the above character with a strip deflector which is carried by the main portion of the presser foot and which extends across the slot and is spaced from the auxiliary or yielding section, so that said section may move vertically within certain limits.

These and other objects will in part be obvious and will in part be hereinafter more fully disclosed.

In the drawings which show by way of illustration one embodiment of the invention,

Figure 1 is a view in side elevation, showing my improved presser foot, the presser guide bar, and the position of the needles relative to the presser foot;

Fig. 2 is a front elevation of the presser foot;

Fig. 3 is a plan view of the presser foot, showing in full lines the position of the movable trimming blade;

Fig. 4 is a side view of the presser foot, viewed from the right in Fig. 2, with the cover plate for the shank of the yielding foot section removed.

Fig. 5 is a perspective view of the presser foot;

Fig. 6 is a bottom plan view of the presser foot; and

Fig. 7 is a perspective view, showing the yielding or movable foot section.

My improved presser foot consists of a supporting shank 1, which is provided with a suitable recess 2 to receive the presser bar of the sewing machine. Said shank is also provided with a rearwardly projecting arm 3, which is forked to engage the auxiliary presser bar of the sewing machine, and this prevents the foot from turning about the presser bar to which it is rigidly secured. Said shank supports a main foot section 4. This main section 4 has an upwardly turned front end portion 5 and also has needle openings 6 and 7. A stitch tongue 8 extends into each needle opening.

Alongside of the main section of the foot there is a yielding or movable section 9, shown in perspective in Fig. 7. This yielding section has a shank 10, which slides between suitable lugs 11-11 on the main shank 1 and a cover plate 12 which is secured to one of the lugs 11 by screws 13, and holds the auxiliary yielding section of the presser foot to the main shank, which permits the same to move up and down thereon. Said shank 10 is provided with a vertical elongated slot 14 into which extends a screw 15, which passes through the cover plate and into the main shank 1. This limits the downward movement of the yielding section of the presser foot when the entire foot is lifted by raising the presser bar. The upward movement of said yielding section is limited by the front lug 11 which is disposed over the inner edge of said section.

A spring 16 is secured to the main shank 1 by a screw 17. This spring projects upwardly and then is bent to project over the shank 10 of the auxiliary presser foot and

the outer end of the spring rests on an upwardly projecting lug 18 formed integral with said shank 10. The yielding section is also provided with an upturned front end portion 9^a.

The main section of the presser foot is cut away at 19. The yielding section extends along side of the main section and has a lateral projection 20 which partially extends into this cut away section 19. The front portion 9^a of the auxiliary foot is, however, spaced from the front end portion 5 of the main section of the foot to form a fabric guiding slot 21. This guiding slot 15 is so arranged that the wall thereof, formed by the main section of the foot, is substantially in line with the center of the forward stitch tongue extending into the needle opening 6.

20. The main section of the presser foot is provided with a recess 23, in which is placed the horizontal stationary blade 24 of the trimming mechanism. Said blade is held in place by a clamping plate 25 secured to the 25 foot by a screw 26. Cooperating with this stationary blade of the trimming mechanism is a movable blade 27. This horizontal movable blade moves over the stationary blade and trims the edges of the fabric passing 30 along the slot 21 and projecting above the upper surface of the lower blade.

Said presser foot is also provided with a strip deflector 27 which is clamped to the main shank 1 of the presser foot by a screw 35 28. This strip deflector extends laterally across the main section of the foot; also across the guiding slot 21 and is bent forwardly and downwardly, as at 29. The lower end of the downwardly projecting 40 bent portion 29 is, however, sufficiently raised above the yielding section 9 of the presser foot so as to permit said foot to move up and down as the thicknesses of fabrics which pass under the foot vary.

45. From the above, it will be apparent that I have provided a presser foot having a guiding slot extending rearwardly from the front end thereof to a point in advance of the needle opening and in which the needle opening is in line with said guiding slot, so that upturned edges of fabric sections may be guided along said slot. These upturned edges of the fabric sections will be severed by the horizontally disposed trimming 55 blades, which operate at the inner end of the slot.

My improved presser foot is especially adapted for covering and joining the edges of sections of fabric. In some cases, as 60 shown in Fig. 2, three sections of fabric a, b and c are fed through the machine, so that their edges are joined and covered and the trimming mechanism trims the upper edges of these sections previous to the join-

ing of the same by the stitching mechanism. 65 As shown in Fig. 2, the two sections c and b are on one side of the foot, while the single section a is on the other side of the foot. The single section of fabric is engaged by the yielding section 9 of the foot, while the superposed layers are engaged by the rigid section 4 of the foot. The yielding section 70 9 is pressed down by the spring 16, so that it makes proper contact with the single section notwithstanding the fact that the two 75 superposed sections hold the main section of the foot slightly raised above the lower surface of the auxiliary yielding section. By mounting the stationary trimmer on the rigid section of the presser foot, I am able so to trim the edge regularly at an even distance above the superposed layers of fabric, which could not be accomplished if this stationary member were mounted on the yielding section. The edges after they have been 80 trimmed pass beneath the main section of the presser foot and the needles 30 and 31 operating through the needle slots 6 and 7 cover the seam. It will be understood of course, that suitable cross stitching mechanism may be used in connection with these needles or the needles may be vibrated for the purpose of producing the covering seam.

It is obvious that minor changes in the details of construction and arrangement of parts may be made without departing from the spirit of the invention, as set forth in the appended claims.

Having thus described my invention, what I claim as new and desire to secure by Letters Patent, is:

1. The combination of a presser foot having a fabric guiding slot extending rearwardly from the front end thereof and having a needle opening in rear of and in line with said slot and a trimming mechanism including a horizontal blade fixed to said presser foot and a horizontally disposed movable blade cooperating with said fixed blade to trim the fabric sections passing along said slot, said presser foot at one side of the slot having a vertically yieldable fabric engaging member whereby said presser foot is adapted to properly engage fabric sections of different thicknesses on opposite sides of the guiding slot.

2. The combination of a presser foot having a fabric guiding slot extending rearwardly from the front end thereof and having a needle opening in rear of and in line with said slot, said presser foot being divided longitudinally to form independent foot sections respectively extending on opposite sides of said slot, means for supporting said sections whereby one section may vertically yield independently of the other section, and a trimming mechanism including horizontally disposed and relatively

movable trimming blades operating at the inner end of said slot to sever fabric sections passing there along.

3. The combination of a presser foot having a fabric guiding slot extending rearwardly from the front end thereof and having a needle opening in rear of and in line with said slot, said presser foot being divided longitudinally to form independent foot sections respectively extending on opposite sides of said slot, a presser bar, means for rigidly connecting one of said sections to the presser bar and means for supporting the other section whereby the same may vertically yield independently of the first named section and a trimming mechanism including a horizontally disposed stationary blade carried by the section rigidly secured to the presser bar and a horizontally disposed movable blade, said trimming blades operating at the inner ends of said slot to sever fabric sections passing there along.

4. The combination of a presser foot having a fabric guiding slot extending rearwardly from the front end thereof and having a needle opening in rear of and in line with said slot, said presser foot being divided longitudinally to form independent foot sections respectively extending on opposite sides of said slot, means for supporting said sections whereby one section may vertically yield independently of the other section, a trimming mechanism including horizontally disposed and relatively movable trimming blades operating at the inner end of said slot to sever fabric sections passing there along, and a strip deflector pro-

jecting across the guiding slot, the front end of said strip deflector being spaced above the yielding section of the presser foot, so as to permit free movement thereof.

5. The combination of a presser foot having a fabric guiding slot extending rearwardly from the front end thereof and having a needle opening in rear of and in line with said slot, said presser foot being divided longitudinally to form independent foot sections respectively extending on opposite sides of said slot, a presser bar, means for rigidly connecting one of said sections to the presser bar and means for supporting the other section whereby the same may vertically yield independently of the first named section, a trimming mechanism including a horizontally disposed stationary blade carried by the section rigidly secured to the presser bar and a horizontally disposed movable blade, said trimming blades operating at the inner ends of said slot to sever fabric sections passing there along, and a strip deflector carried by the section of the foot rigidly attached to the presser bar and projecting across said guiding slot, the front end of said strip deflector being spaced above the yielding section of the presser foot, so as to permit free movement thereof.

In testimony whereof I affix my signature in the presence of two witnesses.

REUBEN B. THOMPSON.
